United States Patent

Des. 235,822
Patented July 15, 1975

235,822

DENTAL CHAIR OR SIMILAR ARTICLE

Francisco Navarrete Hernandez, Giorgioni 37-4,
Mexico City 19, Mexico

Filed Oct. 10, 1973, Ser. No. 405,189

Term of patent 14 years

Int. Cl. D6—01

U.S. Cl. D6—22

Fig. 1.

FIG. 1 is a front perspective view of a dental chair showing my design;

FIG. 2 is a view in side elevation thereof.

The rear of the chair is plain and unornamented.

I claim:

The ornamental design for a dental chair or similar article, as shown and described.
